DESIGN FOR A TAPE MEASURE

Herbert F. Ritter, Bogota, N. J.

Application January 15, 1935, Serial No. 54,864

Term of patent 7 years

To all whom it may concern:

Be it known that I, Herbert F. Ritter, a citizen of the United States, residing at Bogota, county of Bergen, State of New Jersey, have invented a new, original, and ornamental Design for a Tape Measure, of which the following is a specification, reference being had to the accompanying drawing, forming a part thereof.

Fig. 1 is a plan view of a tape measure showing my new design.

Fig. 2 is an edge view of the tape measure shown in Fig. 1.

I claim:

The ornamental design for a tape measure, as shown.

HERBERT F. RITTER.
